ASSOCIATING AND FOLDING MECHANISM

**Howard M. Barber, Pawcatuck, Conn., assignor to
C. B. Cottrell & Sons Company, Westerly, R. I.,
a corporation of Delaware**

Application October 26, 1939, Serial No. 301,338

11 Claims. (Cl. 270—32)

The object of my invention is to provide novel means for selectively handling two different sized products of a rotary web printing press, one where the form cylinder is an even number of plates around and the other where the form cylinder is an odd number of plates around.

My invention more particularly comprises two independently operated units for selectively cutting, folding and delivering products of the press when running four or five plates around the form cylinder, the associated printed webs in the first instance being cut into two two plate length signatures, folded and delivered in duplicate products to the same delivery; and in the second instance into two and three plate length signatures, folded and delivered, the once folded two plate length signatures to one delivery and the twice folded three plate length signatures to another delivery.

20. A practical embodiment of my invention is represented in the accompanying drawings, in which

Fig. 1 represents a side elevation with the parts in the positions they assume to utilize the first cutting, folding and delivery unit, the second unit being silenced;

Fig. 2 represents a similar view with the parts in the positions which they assume to utilize the second cutting, folding and delivery unit, the first unit being silenced; and

30. Fig. 3 represents a detail longitudinal central section through the three cylinders of the first unit.

The first cutting, folding and delivery unit is designed, in the present instance, to handle the product of a rotary web printing press in which the form cylinder is four plates around, all of the product being delivered to one delivery. This first cutting, folding and delivery unit comprises the coating cutting and folding cylinders 1, 2, 35 the delivery cylinder 3 and the delivery 4. The delivery 4 is shown as a horizontally disposed traveling endless carrier.

The cylinder 1 is provided with diametrically opposed cutter knives 5, 5 and adjacent impaling pins 6, 6. This cylinder is also provided with diametrically opposed tucking blades 7, 7.

The cylinder 2 is provided with diametrically opposed cutting blocks 8, 8 which coat with their knives 5, 5, and diametrically opposed folding jaws 9, 9 which coat with the tucking blades 7, 7.

The cylinder 3 is provided with three equally spaced sets of grippers 10, 10 which coact with the folding jaws 9, 9.

55. Stationary cams 11, 12 may be employed to

insure the proper operation of the folding devices and grippers for folding the signatures and delivering them to the delivery 4.

The delivery cylinder 3 is driven at a lesser surface speed than the cutting and folding cylinders 1, 2, in the present instance through the train of gears 13, 14, 15, 16. The cylinders 1, 2 are driven from the drive shaft 17 through the train of gears 18, 19, 20, the gear 20 meshing with the gear 13 of the cylinder 2. 10

The gear 19 is removable or shiftable for silencing the first cutting, folding and delivery unit, when so desired.

The printed webs are associated by the pair of coating rollers 21, 22, the roller 22 being positively driven from the drive shaft 17 through the bevel gears 23, 24, shaft 25, bevel gears 26, 27, shaft 28 and bevel gears 29, 30.

Curved sheet guides 31, 32 are located underneath the cylinders 1, 2 upon opposite sides of a cross bar 33 having a slot 34 therethrough, said cross bar having an arm 35 to permit the bar to be rotated a quarter turn to prevent or permit, as the case may be, the passage of the associated webs therethrough to the second cutting, folding and delivery unit.

The second cutting, folding and delivery unit is, in the present instance, designed to handle the product of a press in which the form cylinder is five plates around, the product being cut into signatures of two and three plate lengths respectively. The signatures of two plate length being once folded and delivered to one delivery and the signatures of three plate length being twice folded and delivered to the opposite delivery. 30 35

This second cutting, folding and delivery unit comprises the coacting cutting and folding cylinders 36, 37, the delivery cylinder 38, its delivery 39, the folding cylinders 40, 41, the delivery cylinder 42 and its delivery 43. The deliveries 39 and 43 are herein shown as horizontally disposed traveling endless carriers. The cylinder 36 is provided with the cutter knives 44, 45 arranged two-fifths of the circumference 45 apart. It is also provided with impaling pins 46 adjacent the cutting blade 44. This cylinder is also provided with the folding blades 47, 48, arranged two-fifths of the circumference apart upon opposite sides of the cutter knife 45. The cylinder 37 is provided with cutting blocks 49, 50 arranged to coact with the cutting knives 44, 45, which cutting blocks are spaced two-fifths of the circumference apart. Midway between these cutting blocks I provide the cylinder 37 55

with a folding jaw 51 arranged to coact with the tucking blade 48.

The delivery cylinder 38 is provided with three sets of grippers 52, 52 also arranged to coact with the folding jaw 51. The stationary cams 53, 54 are employed to insure the proper operation of the folding devices and grippers for folding the signatures of two plate length and delivering them to the delivery 39. The cylinder 10 40 is provided with the folding jaw 55 arranged to coact with the tucking blade 47 on the cylinder 36. This cylinder is also provided with the tucking blade 56 which is arranged to coact with the folding jaw 57 on the cylinder 41. The delivery cylinder 42 is shown as provided with three sets of equally spaced grippers 58, 58, 58 arranged to coact with the folding jaws 57. Stationary cams 59, 60, 61 may be employed to insure the proper operation of the folding devices and grippers for twice folding the signatures of three plate length and delivering them to the delivery 43.

The cylinder 36 is driven from the drive shaft 17 through the train of gears 18, 59 and 60, the gear 59 being removable or shiftable for silencing the second unit when the first unit is being used. The cylinder 37 is provided with a gear 61 which meshes with the gear 60 and which drives the delivery cylinder 38 at a lower surface speed than the cylinders 36 and 37 through the train of gears 62, 63, 64. The cylinders 40 and 41 are driven at the surface speed of the cylinder 36 through the gears 65 and 66, the cylinder 65 meshing with the gear 60 of the cylinder 36 and 35 also with the gear 66 of the cylinder 41.

The delivery cylinder 42 is driven at a lower surface speed than the cylinder 41 through the train of gears 67, 68, 69. When the associated webs are passed through the first unit to the second unit they are led between the guide rollers 70, 71, the guide roller 71 being driven from the gear 61 through the gears 72, 73.

Curved guides 74, 75 are located beneath the cylinders 36, 37 upon opposite sides of a crossbar 45. 76.

In operation, when it is desired to handle a product of the press with four plates around the form cylinder the second unit is silenced by removing or shifting the gear 59 out of mesh with the drive shaft gear 18. The gear 19 is put into mesh with the drive shaft gear 18 thereby operatively connecting the first unit to the drive shaft. The bar 33 is turned to close its slot 34 to the passage of the associated webs therethrough. As 55 the associated webs pass between the cylinders 1 and 2 the leading ends of the webs are engaged by the impaling pins 6 immediately succeeding the operation of the coacting cutters 5 and 8 and are carried around on the cylinder 1 until the 60 tucking blade 7 on the cylinder 1 coacts with the folding jaw 9 on the cylinder 2 to fold the signature off on to the said cylinder 2. At the proper time the next signature is severed by the coaction of the cutters and the folding operation is 65 repeated. The once folded signatures are successively taken by the grippers 10 on the delivery cylinder 3 and deposited thereby on to the delivery carrier 4.

When it is desired to handle a product of the 70 press with five plates around the form cylinder the first printing unit is silenced by the removal or shifting of the gear 19 out of mesh with the drive shaft gear 18 and the meshing of the gear 59 with the drive shaft gear 18 to operatively 75 connect the second unit thereto.

The cylinders of the first unit are turned to bring one of the flattened surfaces 77, 77 of the cylinder 1 opposite the surface of the cylinder 2 to permit the free passage of the associated webs therebetween. The bar 33 is turned to permit the passage of the associated webs through the slot 34 to and between the guide rollers 70, 71 and between the cylinders 36, 37 of the second unit. The associated webs of five plate length are cut into one signature of two plate length 10 and one signature of three plate length. The signature of two plate length is cut with tabs connecting it to the signature of three plate length so that the leading ends of the signature of two plate length are carried around the cylinder 36 by the signature of three plate length until separated therefrom by the co-action of the folding devices 48, 51 on the cylinders 36, 37. This once folded signature of two plate length is then taken by the delivery cylinder grippers 52 20 and deposited on the delivery carrier 39.

The signature of three plate length is first folded one-third its length by the folding devices 47, 55 on the cylinders 36, 40 and it is again folded two-thirds its original length by the folding 25 devices 56, 57 on the cylinders 40, 41. The twice folded signature is then taken by the grippers 58 on the delivery cylinder 42 and deposited on the delivery carrier 43.

It is evident that various changes may be re-sorted to in the construction, form and arrangement of the several parts without departing from the spirit and scope of my invention, and hence I do not intend to be limited to the particular embodiment herein shown and described, but 35

What I claim is:

1. In an associating and folding mechanism, two selectively operated cutting, folding and delivery units, one unit being arranged to handle a product where there are an even number of 40 plates around the press form cylinder, and the other unit being arranged to handle a product where there are an odd number of plates around the press form cylinder and web associating and forwarding rollers common to both units. 45

2. In an associating and folding mechanism, two selectively operated cutting, folding and delivery units, one unit being arranged to handle a product where there are four plates around the press form cylinder, and the other unit being 50 arranged to handle a product where there are five plates around the press form cylinder and web associating and forwarding rollers common to both units.

3. In an associating and folding mechanism, two selectively operated cutting, folding and delivery units, one unit being arranged to handle a product where there are an even number of plates around the press form cylinder, and the other unit being arranged to handle a product where there are an odd number of plates around the press form cylinder and web associating and forwarding rollers common to both units, a single delivery being provided for the first named unit and two deliveries being provided for the 60 second named unit. 65

4. In an associating and folding mechanism, two selectively operated cutting, folding and delivery units, one unit being arranged to handle a product where there are four plates around 70 the press form cylinder, and the other unit being arranged to handle a product where there are five plates around the press form cylinder and web associating and forwarding rollers common to both units, a single delivery being pro- 75

vided for the first named unit and two deliveries being provided for the second named unit.

5. In an associating and folding mechanism, two selectively operated cutting, folding and delivery units, one unit being arranged to handle a product where there are an even number of plates around the press form cylinder, and the other unit being arranged to handle a product where there are an odd number of plates around 10 the press form cylinder, a common main drive being provided for both units, and means for connecting the drive to the one or the other of said units.

6. In an associating and folding mechanism, 15 two selectively operated cutting, folding and delivery units, one unit being arranged to handle a product where there are four plates around the press form cylinder, and the other unit being arranged to handle a product where there are 20 five plates around the press form cylinder, a common main drive being provided for both units, and means for connecting the drive to the one or the other of said units.

7. In an associating and folding mechanism, 25 two selectively operated cutting, folding and delivery units, one unit being arranged to handle a product where there are an even number of plates around the press form cylinder, and the other unit being arranged to handle a product where there are 30 an odd number of plates around the press form cylinder and web associating and forwarding rollers common to both units, the first named unit comprising a pair of coacting cutting and folding cylinders and a delivery cylinder coacting with one of the cutting and folding cylinders, and the second named 35 unit comprising cutting, folding and delivery cylinders coacting to deliver a once folded signature of an even number of plates length to one point, and a twice folded signature of an odd 40 number of plates length to another point.

8. In an associating and folding mechanism, two selectively operated cutting, folding and delivery units, one unit being arranged to handle a product where there are four plates around 45 the press form cylinder, and the other unit being arranged to handle a product where there are five plates around the press form cylinder and web associating and forwarding rollers common to both units, the first named unit comprising a pair of coacting cutting and folding cylinders and a delivery cylinder coacting with one of the cutting and folding cylinders, and the second named unit comprising cutting, folding and delivery cylinders coacting to deliver a once folded 50 signature of two plates length to one point and a twice folded signature of three plates length to another point.

9. In an associating and folding mechanism,

two selectively operated cutting, folding and delivery units, one unit being arranged to handle a product where there are an even number of plates around the press form cylinder, and the other unit being arranged to handle a product where there are an odd number of plates around the press form cylinder, the first named unit comprising a pair of coacting cutting and folding cylinders and a delivery cylinder coacting with one of the cutting and folding cylinders, and the second named unit comprising cutting, folding and delivery cylinders coacting to deliver a once folded signature of an even number of plates length to one point, and a twice folded signature of an odd number of plates length to another point, a common main drive for both units, and means for connecting the drive to the one or the other of said units.

10. In an associating and folding mechanism, two selectively operated cutting, folding and delivery units, one unit being arranged to handle a product where there are four plates around the press form cylinder, and the other unit being arranged to handle a product where there are five plates around the press form cylinder, the first named unit comprising a pair of coacting cutting and folding cylinders and a delivery cylinder coacting with one of the cutting and folding cylinders, and the second named unit comprising cutting, folding and delivery cylinders coacting to deliver a once folded signature of two plates length to one point and a twice folded signature of three plates length to another point, a common main drive for both units, and means for connecting the drive to the one or the other of said units.

11. In an associating and folding mechanism, two selectively operated cutting, folding and delivery units, one unit being arranged to handle a product where there are an even number of plates around the press form cylinder, and the other unit being arranged to handle a product where there are an odd number of plates around the press form cylinder, the first named unit comprising a pair of coacting cutting and folding cylinders and a delivery cylinder coacting with one of the cutting and folding cylinders, and the second named unit comprising two coacting cutting and folding cylinders, a delivery cylinder coacting with one of the cutting and folding cylinders, a first folding cylinder coacting with the other cutting and folding cylinder, a second folding cylinder coacting with the first folding cylinder and a delivery cylinder coacting with the second folding cylinder, a common main drive for both units, and means for connecting the drive to the one or the other of said units.

HOWARD M. BARBER.
